United States Patent

Des. 241,863

Patented Oct. 12, 1976

241,863

EXERCISING PLATFORM

Edward L. Friedl, Los Angeles, Calif.
(8406 Wilbur St., Northridge, Calif. 91324)

Filed Mar. 10, 1975, Ser. No. 556,817

Term of patent 14 years

Int. Cl. D21—02

U.S. Cl. D34—5 K

FIG. 1 is a top perspective view of an exercising platform, showing my new design;

FIG. 2 is a bottom perspective view thereof;

FIG. 3 is a top plan view thereof; and

FIG. 4 is a side elevational view thereof.

I claim:

The ornamental design for an exercising platform, substantially as shown.
